(57) **CLAIM**

The ornamental design for a display screen with animated graphical user interface, as shown and described.

DESCRIPTION

FIG. 1 is a front view of a display screen with animated graphical user interface showing a first image of our new design;

FIG. 2 is a second image thereof; and,

FIG. 3 is a third image thereof.

The appearance of the animated graphical user interface sequentially transitions between the images shown in FIGS. 1-3. The process or period in which one image transitions to another image forms no part of the claimed design.

The broken lines shown represent unclaimed subject matter of the display screen with animated graphical user interface and form no part of the claimed design.
